PAPER FEEDING MECHANISM FOR
STATISTICAL MACHINES

Richard Everest Baldwin, Thornton Heath, England, assignor to The Accounting and Tabulating Corporation of Great Britain Limited, London, England

Application July 3, 1934, Serial No. 733,559
In Great Britain July 6, 1933

11 Claims. (Cl. 235—58)

This invention relates to paper feeding mechanism for statistical machines, tabulating machines, or calculating machines.

According to the present invention paper feeding mechanism for a machine having a platen and line spacing mechanism comprises in combination means for rotating the platen a constant amount independently of the line spacing mechanism to eject a sheet, auxiliary paper feeding means for feeding paper to the platen and means for operating said auxiliary feeding means simultaneously with the mechanism for rotating the platen to eject a sheet. By this means during the listing of items on one sheet, the following sheet 5 may be placed in readiness in the auxiliary feeding means, so that when the first sheet is ejected the following sheet is simultaneously fed into printing position in the platen. This may occur immediately after the printing operation of the last line of the outgoing sheet. In this way no 10 time is lost between the completion of the listing operation on one sheet and the commencement of the listing operation on the next sheet.

Preferably, means is provided for releasing the auxiliary paper feeding means after it has fed a sheet and for causing the auxiliary means to grip the sheet just prior to a feeding operation.

For example, the auxiliary feeding means may comprise pairs of feed rolls and means for separating the first pair of feed rolls after a feeding operation, so that a new sheet may be inserted between them and for bringing the feed rolls together to grip the paper just before the commencement of a feeding operation.

The mechanism for actuating the auxiliary feeding means simultaneously with the paper ejecting means may be connected to a source of power by actuation of a manually operable control member, such as, a key.

In cases, however, where the machine is adapted to print a total automatically, or by operation of a hand control, after listing a series of items, or printing a single item, the auxiliary feeding means and the paper ejecting means may be operated from the total taking or item printing mechanism, so as to operate whenever a total or item is printed.

The sheets on which the machine is intended to print are usually provided with headings, and accordingly each sheet must be inserted in the machine in such a position that the first line of print will appear immediately below the heading.

In order that this setting of the paper may be carried out by the operator when inserting a new

sheet, the auxiliary feeding means may be provided with an indicator, past which the sheet may be fed until the lower edge of the heading is opposite the indicator, thereby showing that the sheet is in the correct position. For example, the machine may have a table situated above the platen, and at a convenient angle for placing the sheet, and reading it. The sheet may be held by the operator against a margin stop on one side, and pushed towards the top of the table, under 5 a guide at each side. A gap may be cut in each guide, the lower edge of which serves as an indicator to which the lower edge of the heading must be set.

This feature of the invention may also be used 15 in cases where it is desired to print a further item on a sheet already containing a series of items, for example, a ledger sheet. In such a case the sheet will be fed in until the last line 20 of figures thereon appears at the lower edge of the indicator.

The invention may be applied to any machine adapted to add and print items on sheets of paper, but is particularly intended for use with record card controlled tabulating machines, 25 wherein the items represented by the holes in the cards are analyzed and transmitted both to type members which print them and to accumulators which accumulate a total of the items.

In the accompanying drawings one construction according to the invention as applied to a record card controlled tabulating machine is illustrated diagrammatically by way of example.

The tabulating machine is of the kind described in United States Patent No. 1,245,502 to James Powers and is provided with total taking mechanism of the kind described in U. S. Patent No. 1,661,684 to A. Thomas.

In the drawings:—

Fig. 1 shows the mechanism in side elevation, 40 Fig. 2 is a side elevation to an enlarged scale of the upper part of the mechanism, and

Fig. 3 shows a detail of the driving mechanism.

Fig. 4 is a detail view of the control mechanism shown in the disabling position.

Fig. 5 is a detail view of the control mechanism shown in the position to permit sheet ejection on each cycle of the machine.

Fig. 6 is an enlarged detail of the mechanism for operating the selective paper guide member 50 with the parts in an initial position.

Fig. 7 discloses the same mechanism as Fig. 6 with the paper guide in its alternate position.

Fig. 8 discloses the same mechanism as Fig. 6 55

and shows the parts in position preparatory to returning the guide to the original position.

Fig. 9 discloses the same mechanism as Fig. 8 and shows the parts in position after returning the guide to the original position.

Fig. 10 is a detailed vertical view of Fig. 6 partially in cross section disclosing the guide member.

Fig. 11 is a detailed vertical view of Fig. 6.

Fig. 12 discloses the mechanism interconnecting the control lever with the no card stop mechanism for stopping the machine after each cycle of the paper feed.

In the construction illustrated in the drawings the platen 1, which is provided with a line spacing mechanism of usual form (not shown) and is also provided with driving mechanism which rotates the platen independently of the line spacing mechanism in order to eject a sheet.

To this end a toothed segment 2 is freely mounted on a shaft 3 in the tabulator (preferably the shaft 3A described in United States Patent No. 1,245,502). Secured to this shaft 3 is an arm 4 carrying a hook 5 engaging over a pin 6 projecting from the segment 2. A spring 7 is attached to the segment at 8 and to the machine frame at 9, this spring tending to turn the segment in a clockwise direction in Fig. 1.

The shaft 3 rocks at each cycle of the tabulator and on its counter-clockwise stroke takes the segment 2 with it through the agency of the hook 5, the latter being returned on the clockwise stroke of the shaft 3 by means of the spring 7.

The teeth of the segment 2 engage with a gear wheel 10 co-axially secured to which is a ratchet wheel 11 held in engagement with a second ratchet wheel 12 by means of a spring washer 13 (Fig. 3).

Co-axially secured to the ratchet wheel 12 is a gear wheel 14 which drives the platen spindle 15 through a further gear wheel 16.

By means of this mechanism when the segment 2 is moved in a counter-clockwise direction, the platen is rotated by a predetermined amount through the ratchets 11 and 12 and the associated gear wheels. On the clockwise stroke of the segment 2 the ratchets slip and the platen remains stationary.

The above described mechanism effects rotation of the platen to eject a sheet on which items have already been printed, the extent of rotation imparted to the platen being always the same and sufficient to eject the sheet whatever the number of items which have been printed on it.

In addition auxiliary sheet feeding means is provided to feed the next sheet into printing position on the platen simultaneously with the ejection of the preceding sheet.

This auxiliary feeding mechanism comprises three pairs of feed rolls 17, 18, 19, 20 and 21, 22 which are driven through gearing from the segment 2.

These three pairs of feed rolls are disposed along a guide or track for the sheets leading from a feed table 23 to the platen 1. The feed table 23 is located in front of the entrance to the first pair of feed rolls 17, 18 from which the sheets pass between guides 24, 25 to the second pair of feed rolls 19, 20. From these latter feed rolls the sheets pass between further guides to the third pair of feed rolls 21, 22 whence they travel to the platen 1.

The guides through which the sheets pass from the second pair of feed rolls 19, 20 to the third pair 21, 22 may be similar to the guides 24, 25

or they may be constructed as shown in Fig. 2 and hereinafter described.

The feed rolls 17, 18, 19, 20, 21, and 22 are driven from the segment 2 through gear wheel 14 and further gear wheels 27, 28, and 29.

In order that the operator may easily insert a new sheet, means is provided for maintaining the first pair of feed rolls 17, 18 spaced apart from one another when they are not rotating.

To this end the upper roll 17 (Fig. 2) is carried on a spindle 31 rotatable in bearings at each end in a link similar to 32, pivoted to the machine frame on a cross shaft 33. The free end of the link 32 shown is pivoted at 34 to one lever 35 of a toggle of which the other lever 36 is pivoted to the first at 37 and is secured to a shaft 38 to which is also secured an arm 39. Pivoted to the arm 39 at 40 is a long link 41 connected at its lower end 42 (Fig. 1) to a triangular plate 43 pivoted to the machine frame at 44.

The lower end 43a of the plate 43 projects into the path of a pin 45 and an L-shaped bracket 46 secured to the segment 2. As the segment 2 reaches the end of its clockwise stroke, the bracket 46 strikes the end 43a of the plate 43 and rocks it in a counter-clockwise direction, thereby pulling the link 41 downwardly and permitting a spring to lower the feed roll 17 into engagement with the roll 18.

The segment 2 then returns in the counter-clockwise direction during which it rotates the platen 1 and feed rolls 17, 18, 19, 20, 21, and 22 through the gears 10, 14, 27, 28, 29, and the ratchets 11 and 12 to eject one sheet from the platen and to feed the following sheet into the platen.

At the end of the counter-clockwise stroke of the segment 2 the pin 45 strikes the end 43a of the plate 43 and rocks it in a clockwise direction thereby pushing the link 41 upwardly and separating the feed rolls 17, 18 to enable a new sheet to be inserted.

If desired the second pair of feed rolls 19, 20 may be made to separate in like manner, and are shown in Fig. 2 constructed so to operate.

As shown in Fig. 2 the roll 19 is mounted on a spindle 47 journaled at each end in an arm 48, pivoted on a cross shaft 49. The arm 48 is pivotally secured at 50 to a lever 51 of a toggle of which the other lever 52 is pivoted to the first at 53 and is secured to the shaft 38 so that the toggle 51, 52 is operated simultaneously with the toggle 35, 36 from the segment 2 through the triangular plate 43 and long link 41. By this means the rolls 17, 18 and 19, 20 are made to open and close simultaneously.

The sheets on which the machine is intended to print are usually provided with headings, and accordingly each sheet must be inserted in the feeding mechanism in such a position that the first line of print will appear immediately below the heading.

In order to ensure correct placing of the sheet thereon the feed table 23 is provided with a marginal stop 54 and each of the guides 24, of which there is a plurality, as shown in Fig. 2, is provided with a slot or window 55.

If the sheet has had no previous items printed thereon it is pushed up the feed table by hand until the lower edge of the heading is visible through the windows 55. On the other hand, if the sheet already contains items it is placed on the feed table so that the last line of printing is visible through the windows 55.

The position of these windows with respect to

the platen is such that at the end of a feeding stroke the sheet will be in a position such that the printing line is immediately below the line which was visible through the windows 55 when the sheet 5 was on the feed table 23.

The operation of the mechanism will now be described.

Assuming that the parts are in the positions shown in Fig. 1 and that there is no sheet in the 10 platen, the shaft 3 rocks at each cycle of the tabulator and when this shaft rocks anti-clockwise from the position shown in Fig. 1 the segment 2 is also positively moved anti-clockwise by means of the hook 5 and pin 6. This movement of the 15 segment 2 rotates the platen through the gear wheel 10, ratchets 12 and 13 and gear wheels 14 and 16. The feed rolls 17, 18, 19, 20, 21, and 22 are also rotated through the gears 27, 28, and 29 driven from the gear 14. Towards the end 20 of the anti-clockwise movement of the segment the pin 45 thereon strikes the end 43a of the plate 43 and rocks it in a clockwise direction thereby opening the feed rolls 17, 18, and 19, 20 through the agency of the link 41 and toggles 35, 25 36, and 51, 52.

The shaft 3 then rocks in a clockwise direction (Fig. 1) and the segment 2 follows this movement under the action of the spring 7. During this movement of the segment 2 the platen 1 remains 30 stationary since the ratchets 11 and 12 slip. Also the feed rolls 17, 18 and 19, 20 remain separated.

While the segment is thus moving in a clockwise direction the operator pushes a sheet up the feed table 23 between the feed rolls 17, 18, now 35 open, to the desired position as determined by the line of print appearing through the windows 55.

Towards the end of the clockwise movement of the segment 2 the bracket 46 thereon strikes the end 43a of the plate 43 and rocks it in an anti-clockwise direction, thereby bringing the feed rolls 17, 18 and 19, 20 together, with the sheet 40 between them.

During the next anti-clockwise movement of the segment 2 the platen 1 and auxiliary feed 45 rolls 17—22 are actuated and feed the sheet into printing position in the platen.

The feed rolls 21 and 22 are so positioned that the head of the paper is in the printing position 50 on the platen before the end of the sheet leaves the feed rolls. A guide 90a is provided which insures that the paper will be conducted directly from the feed rolls to the platen.

The segment 2 then again rocks in a clockwise direction during which time the printing operation 55 is effected on the sheet which is in the platen by means of the normal printing mechanism of the tabulator (not shown).

While this printing operation is taking place 60 the operator places the next sheet in position between the feed rolls, and during the next anti-clockwise stroke of the segment 2 the sheet which was in the platen is ejected and simultaneously the following sheet, already placed in position in the feed rolls, is fed into printing position in the 65 platen.

In the foregoing description the segment 2 rocks at each cycle of the tabulator so that a sheet is ejected and a new sheet fed in at each 70 cycle. With this arrangement only one item is printed on each sheet and although in some cases only one item is required to be printed it is also necessary to provide means whereby a sheet is retained on the platen during the printing of a number of items and if desired their total.

75 To this end a stop arm 60 is provided which can

be set so as to engage a pin 61 on the segment 2 when the latter reaches the end of its anti-clockwise stroke.

This stop arm 60 is notched and is pivoted at 62 to a bracket 63 secured to the machine frame 5 and has a downward extension 64 carrying a pin 65 engaging in a notch 66 formed on an arm 67 pivoted at 68 to the lower end of a lever 69 pivoted at 70 to an arm 71 secured to a shaft 72 in the machine which is stationary during adding 10 cycles of the machine, but rocks on a total cycle. (This shaft 72 is known as the front total shaft of the tabulator).

Pivoted at 73 to a bracket 74 is a manually operable control lever 75 having an upward arm 76 15 pivoted to the lever 69 by a pin 77. This pin 77 is free to slide in a slot 78 in the upward arm 76 of the control lever and the lever 69 is also free to move longitudinally by reason of the slot 69a in its upper end. The pin 77 can engage with one 20 or the other of three notches 79 in the upper edge of the bracket 74 whereby the control lever 75 is held in the position to which it has been set.

In Fig. 1 the parts are shown in the position 25 which they occupy when the control lever 75 is set to cause operation of the feed mechanism on total cycles only and the front total shaft has rocked to remove the stop arm 60 from the path of the pin 61 on the segment 2.

In order to make the auxiliary feed rolls operate in the manner described above at each cycle of the tabulator whereby a sheet is ejected and a new one fed in each time an item is printed the control lever 75 is operated to its lowest position 30 as shown in Figure 5. At this time the total shaft 72 is stationary and therefore the upper end of the arm 76 of the lever 75 pulls the lever 69 in an anti-clockwise direction about the pivot 70 whereby the notched arm 67 is moved over to the right in Figure 1, and in so doing rotates arm 60 anti-clockwise thereby removing it from the path of pin 61.

If at the time that the operator moves the lever 75 to the item printing position the segment 2 was held by arm 60 (disabled position) the movement of notched arm 67 to the right will cause it to ride up over the pin 65 thereby stretching a spring 80 connected at one end to the pin 65 and at the other end to a pin 81 on the notched arm 67. The parts are 35 held in this position by the pin 77 engaging in the right-hand notch 79. The length of the arm 60 is such that it holds the segment 2 not in its extreme position, but slightly away from it so that with the parts in the position just described when the shaft again rocks in an anti-clockwise direction, the hook 5 towards the end of the stroke will 40 pull the segment 2 to the extreme limit of travel, thereby relieving the arm 60 of the load due to the spring 7. The spring 80 then rocks the lower end 64 of the arm 60 in an anti-clockwise direction, as shown in dotted lines in Fig. 4, whereby the arm 60 is removed from the path of the pin 61. A stop 82 attached to the bracket 63 limits this movement of the extension 64 of the arm 45 60. The arm 60 is now entirely out of the path of the pin 61 so that at each cycle of the machine the segment 2 can rock and thereby eject a sheet on every cycle of the tabulator.

If it is desired to make the sheet feeding mechanism operate only on a total cycle, the lever 75 is moved to the middle position as shown in Fig. 1.

After the first adding cycle the stop 60 remains in engagement with the pin 61 since by 75

the upward movement of the lever 78 to the mid position the notched arm 87 was moved to the left thereby placing the stop 88 in position to contact the pin. When the total shaft 38 rocks clockwise on a total cycle, the arm 88 is swung counter-clockwise about the pin 77 as a pivot so that its lower end pulls the notched arm 87 over to the right in Fig. 1 whereby the stop 88 is removed from the path of the pin 81 as described above.

It is to be understood that the normal paper feed mechanism is operative during the printing of the items preceding the total cycle which will cause the present device to eject the sheet. This is permitted by the ratchet drive mechanism 11 and 12.

In order to put the feeding mechanism entirely out of operation the control lever 78 is moved upwardly to the position shown in Fig. 4. This motion pushes the notched arm 87 over to the left whereby the stop arm 88 is moved into the path of the pin 81 and remains there. After the first cycle the segment 2 is held at its extreme 25 counterclockwise position.

In the case of the mechanism described above reference was made to guides 24 and 25 between which the sheets pass from the feed rolls 17, 18 to the feed rolls 19, 20 and it was stated that similar guides could be provided to conduct sheets from the feed rolls 19, 20 to the third pair of feed rolls 21, 22. In such a case, however, the total length of the path from the feed rolls 17, 18 to the platen must be equal to approximately twice 35 the length of a sheet.

According to a further feature of the invention means may be provided for causing sheets to overlap in the guides, that is to say when one sheet is in the platen, the next one can be inserted in the feed rolls to such an extent as to lie underneath or on top of part of the sheet already in the platen whereby the length of path between the first pair of feed rolls and the platen can be materially reduced.

To this end alternative paths are provided for conveying the sheet from the feed rolls 19, 20 to the feed rolls 21, 22. These paths are formed by providing a central guide 85 (Fig. 2) and two outer guides 86 and 87. At the upper end 88 of the central guide 85 is pivoted a flap 89, the position of which determines the path of the sheet. Adjacent the third pair of feed rolls 21, 22, the two paths formed by these guides converge into a single path 90 so that only one sheet at a time 55 enters the platen. The flap 89 is operated by an arm 91 secured to the toggle actuating shaft 38 already described. To this arm 91 is pivoted at 92 a link 93 having two abutments 94 and 95 at its free end. The link 93 passes between two long pins 86 and 87 projecting from lever 88a pivoted at 90 to the frame 28 and are connected at their outer ends by a plate 98 (Figs. 4 and 9).

The assembly comprising the lever 88a, pins 86, 87 and plate 98 is pulled in an anti-clockwise direction by a spring 100 connected at one end to a pin 100a on the lever 88a and at the other end to a pin 100b on the frame.

With the parts in the position shown in Figs. 1 and 2 when the shaft 38 rocks in a clockwise direction, the link 93 is pushed upwardly and its free end between the abutments 94 and 95 engages with a pin 101 on a triangular plate 102, pivoted at 103 to the frame 28. This position of the parts is shown in Fig. 6. Further upward

movement of the link 93 turns the plate 102 in a clockwise direction about its pivot 103 into the position of Fig. 7. During this clockwise movement of the plate 102 the pin 101 therein engages the abutment 94 and turns the link 93 counter-clockwise thereby bringing the other abutment 5 clear of a second pin 105 on the plate 102 (Fig. 7 position), the purpose of which will be described later.

As the link 93 turns thus counter-clockwise, it 10 causes rotation of the lever 88a about pivot 98 against the action of spring 100. The plate 102 is connected by a spring 104 to the flap 89. When the plate 102 is rocked by the upward movement of link 93 over from the position shown in Figs. 1 and 2 to the other side of the pivot 88 of the flap, (Fig. 7 position) the latter rocks over to its other position (shown in Fig. 1) under the action of the spring 104 whereby the next sheet 15 will be guided to pass between the guides 85 and 87.

When the shaft 38 rocks in a counter-clockwise direction the link 93 is pulled downwardly and as soon as the abutment 94 has moved clear of the pin 101 the spring 100 acting on the lever 88a 20 returns the link 93 to its mid position. The link 93 and assembly 86, 87, 88, 88a are now in the position shown in Figs. 1 and 2 while the plate 102 and flap 89 remain in the position shown in Fig. 7.

On the next clockwise movement of the shaft 38 the link 93 is pushed upwardly, but since the plate 102 is in the Fig. 7 position the end of the link 93 between the abutments 94 and 95 engages with the pin 105 in the plate 102 (Fig. 8 position) 35 and rocks the latter in a counter-clockwise direction to the position shown in Fig. 9. During movement of the plate 102 from the position shown in Fig. 8 to that of Fig. 9 the pin 105 engages with the abutment 95 and turns the link 93 aside in a clockwise direction thereby bringing the abutment 94 clear of the pin 101.

In spite of the provision of two guides to permit the overlapping of sheets fed into the machine, it is obvious that, when the feeding mechanism is set to operate on each cycle the operator would have difficulty keeping pace with the machine to insert a new sheet unless the machine is automatically stopped after a single item has 45 been printed and the sheet ejected.

In order to permit the operator time to insert a new sheet means may be provided for stopping the machine automatically after each cycle when the lever 78 is set in its lowermost or single cycle 55 position as shown in Fig. 5. After the machine has stopped and the sheet inserted it may be restarted at will by the operation of a starting button.

In normal operation the tabulator is stopped after all the cards have passed by the following 60 well known mechanism disclosed and described in the U. S. patent to A. Thomas 1,938,228. A pin descends on each card in turn during the sensing operation. If there is no card in the pin box this pin 110 (Fig. 12) descends lower than if a 65 card were there and, as it does so, pushes downward one end of a hooked lever 111, whereby the hook 112 is raised clear of the end of a bell crank 113 having a hook 114 formed thereon. The bell crank 113 is pivoted on plate 130 which is secured 70 to an eccentric strap arm 131. The bell crank 113 is held in upright position on plate 130 by a spring 132 and a pin 133 in the bell crank which bears against the plate 130. In this position the hook 114 is adapted to engage a projection 116 75

on a push rod 117. Rotation of eccentric 115 causes the hook 114 to cooperate with projection 118 drawing the push rod 117 to the right whereby a clutch (not shown) transmitting the drive of the 5 tabulator is disengaged, thereby stopping the tabulator.

In order that this mechanism may be used to stop the machine at each cycle when the control lever 75 is set to cause operation of the said feeding mechanism on each cycle, the control lever 10 75 controls the hooked lever 111 through a linkage comprising links 118, 119, 120 and 121 so that when the control lever 75 is moved the link 121 follows due to the spring 122.

15 The spring 122 tends to rotate the plate 119 counterclockwise about its pivot thereby forcing links 120 and 121 upward and drawing link 118 to the right. When lever 75 is positioned in either its uppermost or midposition the links 20 120 and 121 follow. As the link 118 is drawn to the right the plate 134 which is freely pivoted on both the link and hook lever 111 is rotated counterclockwise about its pivot in lever 111 rotating the lever counterclockwise thereby lowering 25 lug 112 into the path of the latch on bell crank 113. When the arm 131 with the plate 130 is moved to the right, the bell crank 113 is held at its upper edge by lug 112 and is rotated clockwise raising hook 114 out of the path of lug 116.

30 If, however, the lever 75 is positioned in the lowermost or single cycle position the links 120 and 121 are forced down moving link 118 to the left thereby bringing the lug 135 on plate 134 into engagement with the lever 111 rotating it in a 35 clockwise direction to raise the lug 112 out of the path of the bell crank 113. When the arm 131 is then drawn to the right by cam 115 the hook 114 engages the lug 116 and moves the rod 117 to the right stopping the machine. The machine 40 may then be restarted at will by the operation of the start key.

In order that the tabulator may be available for all its ordinary functions, the sheet feeding mechanism according to the invention is preferably 45 constructed in the form of a detachable unit. To this end the frame or casing 26 of the sheet feeding mechanism is provided with a pin 125 on each side near the top and at the back, there being also two slots 126 cut in the lower end of 50 casing 26. The mechanism is attached to the tabulator by lowering the two pins 125 in the slots cut in bracket 127 secured to the main frame of the tabulator, the sheet feeding unit being then swung about these pins until the slots 55 126 in the casing 26 of the sheet feeding mechanism engage and pass over corresponding screw-threaded studs 128 mounted in the tabulator frame. The unit is then secured by means of nuts 129 screwed on to these studs.

60 The feed table 23 above referred to is provided with a marginal stop 54 and preferably this stop 54 is adjustable laterally. To this end the stop may be in the form of a bar and provided with two pins which enter slots in the feed table. 65 These slots are parallel and inclined to the horizontal edges of the feed table. By moving the marginal stop bar in the slots, it is maintained parallel to the lateral edge of the feed table while adjusting its position relatively thereto.

70 In order to provide a greater degree of adjustment, two sets of inclined slots may be provided and the stop bar placed in one or other of these slots.

In order to enable the stop bar to be readily 75 removed, one of the pins which it carries is pro-

vided with an elongated head parallel with the bar. The other pin is screw threaded and provided with a nut. To remove the bar the nut is unscrewed and removed and the bar swung round about the other pin until the elongated head 5 registers with an inclined slot. The bar is then lifted clear and can be placed in another slot if desired.

It is to be understood that the drawings disclose only one embodiment of the device which 10 may be varied widely without departing from the original conception.

What I claim is:—

1. In sheet feeding mechanism for a statistical machine having a platen and line spacing mechanism therefor, the combination of means for rotating the platen to a constant extent independently of the line spacing mechanism to eject a sheet from the platen, auxiliary sheet feeding means having sheet gripping members disposed 15 to feed a sheet to the platen, means for operating said auxiliary sheet feeding means simultaneously with the means for rotating the platen independently of the line spacing mechanism, means for releasing said sheet gripping means after a feeding operation to permit insertion of a new sheet 20 and means for causing said auxiliary feeding means to grip the sheet prior to a feeding operation.

2. In sheet feeding mechanism for a statistical 30 machine having a platen and line spacing mechanism therefor, the combination of means for rotating the platen to a constant extent independently of the line spacing mechanism to eject a sheet from the platen, auxiliary feed rolls disposed 35 to feed a sheet to the platen, means for rotating said auxiliary feed rolls simultaneously with the rotation of the platen to eject a sheet, means for opening said auxiliary feed rolls at the end of a feeding operation to permit the insertion 40 of a new sheet therebetween, and means for moving said auxiliary feed rolls into engagement prior to a feeding operation.

3. In sheet feeding mechanism for a statistical 45 machine having a platen and line spacing mechanism therefor, the combination of auxiliary feed rolls disposed to feed a sheet to the platen, a rocking driving member, a connection between said driving member and the platen and the auxiliary feed rolls, operative in one direction of movement 50 of said driving member only, whereby the platen is rotated to a constant extent independently of the line spacing mechanism to eject one sheet during each movement of said driving member in one direction and the auxiliary feed rolls are 55 simultaneously rotated to feed the following sheet to the platen, means for opening and closing said auxiliary feed rolls, a projection on said rocking driving member adapted to engage said opening and closing means at the end of each operative 60 stroke of the driving member to effect opening of the auxiliary feed rolls and a second projection on the driving member adapted to engage the opening and closing means at the end of the idle stroke of the driving member to effect closing of 65 the auxiliary feed rolls.

4. Sheet feeding mechanism according to claim 3 wherein the auxiliary feed roll opening and closing means comprises arms pivoted to the machine frame and carrying one feed roll of a pair, a toggle 70 having the outer end of one of its levers pivoted to one of said arms and the outer end of its other lever pivoted to the machine frame, a transmission arm pivoted to the machine frame with its free end disposed in the path of the projections on 75

the rocking driving member, and a link connecting the transmission arm to one of the toggle levers.

5. The combination with sheet feeding mechanism according to claim 1 of guides serving to direct the sheets from the auxiliary feeding means to the platen, said guides having a gap formed therein in a position distant from the platen by an amount equal to the feed effected by the auxiliary feeding means less one line space, where-
10 by by inserting a partially filled sheet in the auxiliary feeding means until the last line of print on said sheet appears through the gap in the guides, the auxiliary feeding means feeds the sheet to a position in which the next printing operation is effected immediately below the last line of print previously appearing on the sheet.

15 6. In a calculating machine having a platen, line spacing mechanism therefor, and printing mechanism, the combination of means for rotating the platen to a constant extent independently of the line spacing mechanism to eject a sheet from the platen, auxiliary sheet feeding means disposed to feed a sheet to the platen means for operating said auxiliary sheet feeding means simultaneously with the means for rotating the platen independently of the line spacing mechanism, and means settable manually to render the sheet feeding mechanism operative at each cycle of the calculating machine, or at a total printing
20 cycle only or to render the mechanism inoperative.

25 7. In sheet feeding mechanism for a statistical machine having a platen and line spacing mechanism therefor the combination of means for rotating the platen to a constant extent independently of the line spacing mechanism to eject a sheet from the platen, auxiliary sheet feeding means disposed to feed a sheet to the platen, means for operating said auxiliary sheet feeding means simultaneously with the means for rotating the platen independently of the line spacing mechanism, and means causing the sheets to pass through the auxiliary feeding means to the platen along one or other of two paths alternately so that one sheet may be overlapped by the following sheet while in the auxiliary feeding means whereby the length of the feed path is reduced.

30 8. Sheet feeding mechanism according to claim 2 including means causing the sheets to pass through the auxiliary feeding means to the platen along one or other of two paths alternately so that one sheet may be overlapped by the following sheet while in the auxiliary feeding means whereby the length of the feed path is reduced.

35 9. In sheet feeding mechanism for a statistical machine having a platen and line spacing mechanism therefor, the combination of auxiliary sheet feeding means disposed to feed a sheet to

the platen, an arcuate rocking driving member, and a connection between said driving member and the platen and the auxiliary sheet feeding means, operative in one direction of movement of said driving member only, a printing mechanism including a stop member for said driving member, actuating means displaceable to move said stop member into the path of said driving member to prevent movement thereof, a manual control, an operative connection between said control member and said actuating means and a connection between the total printing mechanism and said actuating means, all so arranged that setting said manual control member in one position moves the stop into engagement with 10 said driving member, while setting the manual control member into a second position removes said stop member from engagement with said driving member, and setting the control member to a third position moves the stop into engagement with said driving member and places said stop under the control of the total printing mechanism to effect removal thereof on a total printing cycle only.

40 10. In sheet feeding mechanism for a statistical machine having a platen and line spacing mechanism therefor, the combination of auxiliary sheet feeding means disposed to feed a sheet to the platen, an arcuate rocking driving member, and a connection between said driving member and the platen and the auxiliary sheet feeding means, a guide channel for said sheets diverging into two channels within the auxiliary feeding mechanism and converging again into a single channel prior to approaching the platen, 35 a shutter dispersed at the point of divergence of the channel and an operative connection between said shutter and said driving member arranged to operate the shutter to close one channel and open the other alternately during the 40 idle stroke of said driving member substantially as described.

45 11. In a calculating machine having a platen, line spacing mechanism therefor, and printing mechanism, the combination of means for rotating the platen to a constant extent independently of the line spacing mechanism to eject a sheet from the platen, auxiliary sheet feeding means disposed to feed a sheet to the platen, a manually operated settable means, means for 50 operating said auxiliary sheet feeding means simultaneously with the means for rotating the platen independently of said line spacing mechanism, and means under control of said settable means for stopping the machine at the end of each cycle to permit the introduction of a new sheet.

RICHARD EVEREST BALDWIN.
